DISPENSING CLOSURE MEANS

John Berry, New York, and Idee D. Wolfson,
Woodmere, N. Y.Substitute for application Serial No. 734,572,
July 11, 1934. This application January 17,
1936, Serial No. 59,564

1 Claim. (Cl. 215—78)

The subject matter of this application was originally disclosed and claimed in our application Serial No. 734,572, filed July 11, 1934. Our invention relates to dispensing closure means 5 and contemplates the provision of a closure cap adapted to be associated with any bottle, container or the like in frequent intermittent and repeated use and which cap is arranged to be substituted for the ordinary bottle or container 10 stopper. Our invention further contemplates the provision of a closure cap which is operated by merely grasping the bottle or container with which it is associated and raised to pouring position without the necessity of releasing the hand 15 from the bottle which it holds and on which the cap is arranged, and which does not require the hand at any time to come into direct contact with the closure cap. Our invention further contemplates a closure cap which will automatically return to the stopper position when the hand of 20 the user is removed from the bottle. Our invention further contemplates the provision of a closure cap which prevents dirt, dust or other like impurities from entering the bottle. Our invention further contemplates the provision of means 25 for preventing the contents of the bottle from dripping over the neck thereof after the liquid is poured therefrom. Our invention further contemplates the provision of indicia means for denoting the contents of the container with which 30 our closure means is associated.

Our invention is particularly advantageous for use with bottles that are frequently used and from which the contents are intermittently poured, such as bar bottles, containing liquors, 35 whiskies, and the like, utilized in the mixing of cocktails. A bartender, using bottles provided with the ordinary stoppers, must remove a plurality of such stoppers each time a cocktail or the like is to be mixed, and place the stoppers on a table or support, prior to pouring out the liquid from the container, thereby incurring the possibility of their falling from the table and subsequent dirtying or loss. Our closure means eliminates the necessity of removing the stoppers ordinarily used from their containers and replacing them and thereby increases the efficiency in repeatedly pouring liquids from a number of separate bottles into a common receptacle in which the liquids so poured are to be mixed together.

Our invention provides a closure means of this kind which is simple in construction, readily assembled and adapted to be made at a comparatively low cost.

55 The various objects of our invention will be

clear from the description which follows and from the drawing in which,

Fig. 1 is a partial section of a further modification of our closure cap.

Fig. 2 is a rear elevation of the device shown 5 in Fig. 1.

In that practical embodiment of our invention which we have illustrated by way of example, the dispensing closure device is provided with an elongated tubular body portion or extension neck 10 38, which is inserted in the neck of a bottle or container, indicated in the drawing by dotted lines, by means of the comparatively long bushing 12 through which the body portion extends and which bushing is made from a compressible 15 or resilient substance such as cork or rubber or the like. The bushing is comparatively long and is downwardly tapered, in order that the closure device may be adapted to be arranged on different bottles or containers having various sized necks 20 20 or openings, as for example, internal diameters of one-half inch to one and one-half inches. If desired, the elongated body portion or extension neck 38 may itself be provided with a downwardly decreasing diameter and have arranged thereon 25 a comparatively thin compressible or resilient bushing, thereby providing a union adjustable to different bottle neck diameters.

In order to more adequately secure the compressible bushing to the body portion 38, an annular bead may be arranged thereon intermediate 30 its ends and provides thereby an anchor which is firmly gripped by the compressible and resilient bushing as it is forced on the device, thereby preventing the body portion from being removed 35 from out of the bushing, upon removal of the closure means from the container with which it is associated.

A pair of outstanding lugs 36, having the end portions thereof inclined upwardly and provided 40 with aligned apertures adapted to receive the pivot pin 37 are disposed on the extension neck 38. The closure cap 39 is arranged adjacent to and in alignment with the downwardly and rearwardly inclined upper face 40 of the extension 45 neck and is provided with a pair of upstanding ears 41, having aligned apertures adapted to receive the pin 37 and thereby pivotally support the cap on the lugs 36, and which ears are assembled on the pin adjacent to and outwardly of the upwardly inclined end portions of the lugs 36.

The finger piece 42 is provided with the flanges 43, having aligned apertures arranged to receive the pivot pin 37, and which are assembled thereon adjacent to and outwardly of the upstanding ears 55

41, to thereby pivotally secure the finger piece thereto.

The wall 44, arranged on the finger piece intermediate the flanges is provided at one end with the upwardly and outwardly beveled edge 45 and the depending flanges 43 are each provided with an outwardly and upwardly tapered wall 48.

Tension means, as the spring 41, are secured to the pivot pin to normally urge the closure cap downwardly about said pivot against the inclined face 46 and retain the closure cap in the stopper position.

In operation the finger piece is rotated downwardly about the pivot into operative position, shown in dotted lines.

The beveled edge 45 is thereby urged into engagement with the upwardly and outwardly tapered wall 48 arranged centrally on the outer end of the closure cap and the walls 46 engage the correspondingly tapered opposed walls 49 arranged on each side of the wall 38.

As previously described the container and the finger piece are simultaneously grasped by the hand and the finger piece is thereby forced downwardly about the pivot. The co-operating beveled walls are thereby forced into operative engagement and urge the closure cap upwardly about the pivot and against the tension means to raise the cap to pouring position.

Upon releasing the hand the tension member automatically returns the closure cap to the stopper position. The finger piece may then be rotated about the pivot pin adjacent to and against the closure cap into the more compact arrangement and assembly shown by the full lines in Fig. 1.

In order to securely and positively lock the closure cap on the extension neck, when the container with which the closure means is associated, is to be shipped or stored away, a lip 50 may be arranged at the outer end of the finger piece to engage the projecting bead 51 projecting from the extension neck.

Intermediate the wall 44 and the lip 50 a curvilinear wall 52 is arranged to provide a resilient and flexible connection to permit the lip 50 to be forced upwardly over the bead 51 and to thereby securely lock the finger piece. The closure cap is thereby forced downwardly by the finger piece which engages it, and the inclined face of the extension neck is forced and extends into the compressible packing 53.

To permit the finger piece to be rotated about

the pivot into operative position, the finger piece may be unlocked by forcing the lip outwardly over the bead, the wall 52 flexing sufficiently for this purpose.

It will be apparent that we have disclosed a dispensing closure means which can readily be associated with containers to replace the ordinary stoppers used therewith and which may be urged into operative position by merely simultaneously grasping the motivating element and the container on which the device is arranged and which may be automatically returned on releasing the hand from the container. It will be further apparent that we have disclosed such a closure means which may be associated with containers of various sizes and which comprises few parts and may be cheaply made.

While we have illustrated our invention as applied to bar bottles, it will be apparent that it may be applied to other types of containers, for example, such as used by a housewife in cooking, milk bottles, tooth paste tubes, automobile radiator caps and the like.

While the invention has been described in detail with specific examples, such examples are illustrative and are not given as limitations, since other modifications within the spirit and scope of the invention will be apparent to those skilled in the art. Hence the invention is to be understood as limited only as indicated, in the appended claim, in which the intent is to set forth all the novelty over the prior art.

We claim:

Closure means arranged on a container comprising a body portion, an outlet arranged thereon, a spring actuated closure element operatively secured to the body portion and normally urged against the outlet in sealing engagement therewith, a motivating element hingedly supported on the closure element and normally extending therefrom in alignment therewith whereby the said motivating element is arranged in one position to engage the closure element to raise said closure element out of sealing engagement and arranged in another position adjacent to and against the closure element and means arranged on the closure element for locking the motivating element adjacent to and against the closure means.
